UNITED STATES PATENT OFFICE.

ALBERT O. ROOD, OF NEW YORK, N. Y., ASSIGNOR TO VINCENT P. TRAVERS,
OF SAME PLACE.

SELVAGE FOR HAMMOCKS.

SPECIFICATION forming part of Letters Patent No. 296,459, dated April 8, 1884.

Application filed October 25, 1883. (No model.)

To all whom it may concern:

Be it known that I, ALBERT O. ROOD, a resident of New York, in the county of New York and State of New York, have invented 5 an Improvement in Selvages for Hammocks, of which the following is a full, clear, and exact description, reference being made to the accompanying drawings, in which—

Figure 1 is a plan view of my improved 10 selvage for hammocks; and Fig. 2 is an enlarged plan view, showing the selvage more open.

This invention relates to hammock-selvages of the class which is described in Letters Patent No. 269,542, of December 26, 1882, for use 15 in hammocks such as are described in Letters Patent No. 277,161, of May 8, 1883, and in other hammocks.

The object of the invention is to render the 20 braided selvage inextensible. That shown in the first-mentioned patent, under strain, will stretch, and so will that shown in the patent of May 8, 1883.

The present invention consists in passing 25 through the selvage, which is composed of braided strands, one or more straight cords, which prevent it from becoming stretched.

It also consists in making one of the body- 30 strands of the hammock that passes through the selvage-loops in one piece with or a con-

tinuation of the strand that extends through the braid.

In the drawings, the letter A represents the braided strands, having the end loops, *a a*, formed thereon, and forming the body of the 35 selvage. Through this selvage is passed longitudinally a strand, *b*, which forms at proper intervals loops *e e*, in which the inner body-strands, *f g*, of the hammock itself are rested. One of these body-strands, *f*, is shown in Fig. 40 1 to connect by the end loop, *h*, with a straight strand, *i*, that passes through the selvage, which is made up of the braided strands. The strand *i* may, if desired, be made separate from the strand *f*. 45

I claim—

1. The selvage for hammocks, A, consisting of a number of braided strands, in combination with the straight strand *i*, passing longitudinally therethrough, as set forth. 50

2. The selvage for hammocks, A, consisting of a number of braided strands, in combination with the strand *b*, having loops *e* formed therein, and the strands *f* and *i*, the strand *i* passing through the selvage and the strand *f* 55 through the loops *e*, substantially as described.

ALBERT O. ROOD.
